UNITED STATES PATENT OFFICE

168,072

STOCKING

Sol Savitz, Philadelphia, Pa.

Application December 31, 1951, Serial No. 18,449

Term of patent 7 years

(Cl. D47—7)

To all whom it may concern:

Be it known that I, Sol Savitz, a citizen of the United States, residing at Philadelphia, in the county of Philadelphia and State of Pennsylvania, have invented a new, original, and ornamental Design for a Stocking, of which the following is a specification, reference being had to the accompanying drawing, forming part thereof.

In the drawing the figure is a rear perspective view of a stocking, showing my new design.

I claim:

The ornamental design for a stocking, substantially as shown.

SOL SAVITZ,
